UNITED STATES PATENT OFFICE.

JOHN A. REED, OF BEATRICE, NEBRASKA.

END-GATE FOR WAGONS.

SPECIFICATION forming part of Letters Patent No. 352,201, dated November 9, 1886.

Application filed April 16, 1886. Serial No. 199,146. (No model.)

To all whom it may concern:

Be it known that I, JOHN A. REED, a citizen of the United States, residing at Beatrice, in the county of Gage and State of Nebraska, have invented certain new and useful Improvements in Gate Ends for Wagon-Boxes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention has relation to gate ends for wagon-boxes; and it consists in the novel construction and arrangement of its parts and the attachments to the box.

Figure 1 is a side elevation of my gate end attached to a wagon-box with the gate end closed. Fig. 2 is a side elevation of the same with the gate end let down. Fig. 3 is a bottom view of the wagon-box and of the gate end closed. Fig. 4 is a bottom view of the same 25 with the gate end let down.

20 My invention is described as follows: To an ordinary wagon-box, A, I secure the following attachments: On each outer side of the box, some two or three feet from the rear end, I secure metal bars 1, in each of which, near their upper ends, is pivoted a turning-button, 2, and about midway the said bars are secured a 25 stationary hook, 3, the purpose of which is hereinafter explained. On the bottom of said wagon-box I securely bolt two slotted plates, 4, by means of bolts and nuts 5, the bolts of which pass through the bottom of the wagon-box, the cross-bar 11, and the slots in said slotted plates 4.

40 Gate end B is made as follows: The planks 6, which close the end of the wagon-box end, are cut a little longer than the said box is deep, and are secured to an upper cross-piece, 7, which is a little longer than the wagon-box is wide, and a lower cross-piece, 8, which is considerably longer than the box is wide. To the front edge of these planks 6 are secured flanges 9, which are wide enough apart to allow the end of the box to go in between. These flanges 9 have to their front

ends an extension, 10, which comes down below and in front of a cross-piece, 11, bolted to the bottom and near the rear end of said box. This arrangement is to prevent the lower end of the said wagon-gate from breaking loose 55 from the box, even under great pressure. To the rear face of the lower cross-bar, 8, of the end-gate B are secured two hooks, 12, which pass through slots in slotted plates 4, which also assist, in conjunction with the bolts and 60 nuts 5, in holding the lower end of the gate end in place. These hooks and slotted plates serve also another purpose, which is herein-after described. These flanges 9 are secured to the front face of the planks 6 of the gate 65 end by a bar of metal, 13, which is screwed or otherwise secured to the lower end and outer face of the same, and the rear end of said bar of metal is turned square out and secured to the front face of the lower cross-bar, 8, and by 70 a bar of metal, 14, which passes through the upper end of said flange 9 and through plank 6, and then has its outer end, 15, turned square down and secured to the rear face of said plank. The front end of said bar of metal has 75 through it an eye, 16, to which is attached, by a link, a plate, 17, having an eye in each end and a button-hole in its center, which works over turning button 2. To the front end of said plate 17 is secured a link chain, 18, the 80 links of which are made to fit between the bar 1 and the hook 3.

This end-gate can be taken entirely off and put on at pleasure. It is put on as follows: It is presented to the rear end of said box on a horizontal line with the bottom of the said box, as shown in Fig. 4, and the bent ends of the hooks 12 are passed through slots in the slotted plate 4. Then the outer end of the said gate is raised, and as it rises the said 90 hooksslide outward until they impinge against the outer end of said slots, and by this means hold the gate down in place. When the gate is brought up, as shown in Fig. 2, the button-hole of the plate 17 is passed over the turning- 95 button 2, then the long end of which is turned forward. This keeps the gate in place. The gate is let down by turning the long end of the button to the rear, and then the plates 17 can be slipped off, and the gate can be let down 100

at any angle and secured by passing the links of the chain 18 between the plate 1 and the hook 3, as shown in Fig. 2.

Having thus described my invention, what I claim as new, and desire to secure by Letters Patent, is—

The combination of the gate end B, as described, the hooks 12, secured to the outer face of the lower cross-piece, 8, slotted plates 4, secured to the bottom of the cross-piece 11 of the said box by means of bolts and nuts 5, cross-piece 11, secured to the bottom and rear

end of said box, plates 14, secured to the upper end of gate B, plates 17, secured to said plates 14, bars 1, secured to the outer face of said box, 15 hooks 3, secured to said bars, and turning buttons 2, pivoted in the upper end of said bars, all substantially as shown and described, and for the purposes set forth.

JOHN A. REED.
